KERF CUTTING APPARATUS

Clyde P. Baldwin, Claremont, N. H., and Harry H. Vanderzee, Michigan City, Ind., assignors to Sullivan Machinery Company, a corporation of Massachusetts

Application September 30, 1941, Serial No. 413,010

3 Claims. (Cl. 262—30)

This invention relates to kerf cutting apparatus and more particularly to improvements in the mounting structure for the cutter bar of the kerf cutting apparatus of a coal mining machine.

An object of the present invention is to provide an improved kerf cutting apparatus. Another object is to provide an improved mounting structure for the cutter bar of a kerf cutting apparatus. Still another object is to provide improved hanger structure for the cutter bar of a coal mining machine. A further object is to provide a novel arrangement of the adjusting means for adjusting the bar along guideways on the hanger frame. A still further object is to provide a novel sliding guide structure for supporting the cutter bar on the hanger frame. Still another object is to provide a cutter bar mounting and cutter bar of novel construction. Still another object is to provide improved means for preventing the transmission of lateral stresses to the guideway-providing elements and the bar securing elements, thereby to increase the strength of the bar. How these and other objects are accomplished, and the advantageous features of the invention, will be best understood from the following detailed description wherein a preferred and illustrative embodiment is set forth, reference for the purpose being had to the accompanying drawings in which:

Fig. 1 is a fragmentary side elevational view of a kerf cutting apparatus in which an illustrative embodiment of the invention is incorporated.

Fig. 2 is a plan view of the kerf cutting apparatus shown in Fig. 1.

Fig. 3 is an enlarged view in longitudinal vertical section taken substantially on line 3—3 of Fig. 2, with certain parts omitted.

Fig. 4 is a cross sectional view taken substantially on line 4—4 of Fig. 3.

Fig. 5 is a cross sectional view taken substantially on line 5—5 of Fig. 3.

Fig. 6 is a horizontal sectional view taken substantially on line 6—6 of Fig. 3, with parts in plan.

In this illustrative construction the invention is shown incorporated in the kerf cutting apparatus, generally designated 1, of a coal mining machine which may be of the same general type as that disclosed in our copending application, Ser. No. 394,410 filed May 21, 1941. It will be evident, however, that various features of the invention may be incorporated in other forms of cutting apparatus and may be associated with mining machines of other types.

The kerf cutting apparatus 1 includes a sup-

port 2 by which a swiveled hanger frame 3 is carried. Mounted on the hanger frame in an improved manner to be later explained, is an elongated cutter bar 4 having an endless cutter chain 5 guided for circulation about its margin. The cutter bar comprises parallel top and bottom plates 6 and 7, held in spaced relation by parallel bar members 8, 8, and these plates and bar members cooperate to provide a guideway 9 about the bar in which the cutter chain 5 is guided for circulation. Carried by the support 2 is a conventional cutter chain drive sprocket 10 (see Figs. 1 and 2) which engages and drives the cutter chain in a well known manner. The bar plates 6, 7 and the bar members 8 are held in assembled relation by suitable rivets and secured by certain of these rivets 11 to the top plate 6 is a plate 12 provided with lateral guides 13, 13. The bottom surface of the plate 12 is longitudinally slotted at 14 and seated in this slot is a key 15 which is fitted within a longitudinal slot 16 in the top plate 6 of the cutter bar. This key 15 receives the lateral thrust of the cutter bar during the kerf cutting operation thereby reducing the shearing stresses imposed on the rivets. The bottom plate 7 is similarly slotted, so that the plates may be interchanged if desired. Projecting downwardly from a projecting portion 17 of the bar hanger frame 3 are blocklike keys 18 slidably received in longitudinally extending, alined key slots 19 in the top surface of the plate 12. Projecting upwardly from the plate 12 between the key blocks 18, 18 is a block or lug 20 integral with the plate 12 and slidably fitted within a longitudinal guideway 21 formed in the hanger frame projection 17. Secured by screws 22 to the opposite sides of the hanger frame projection 17 are gib members 23, 23, webbed for reinforcement, and having inwardly directed top ledges 24 provided with inner inclined surfaces 25 engaging corresponding inclined surfaces 26 on the hanger frame. These gib have inwardly directed bottom flanges 27 underlying and engaging the plate guides 13. The key blocks 18 received in the plate slots 19 receive the lateral thrust of the cutter bar during the kerf cutting operation thereby reducing the lateral stresses transmitted to the gibs, and the latter receive the thrusts of the cutter bar in a vertical direction, i. e., in a direction at right angles to the direction in which lateral thrusts are imposed, in an obvious manner.

For adjusting the cutter bar in an endwise direction relative to its guides on the hanger frame 53, 3, is an adjusting screw 28 engaging a nut 29

herein formed integral with the slide block 20 (see Figs. 3, 4 and 6). A head 38 of the screw engages the front wall 31 of the hanger frame projection 17 and this screw head is polygonally formed for the reception of a suitable turning instrument. When the adjusting screws 22 for the gibs 23 are loosened, the adjusting screw 29 may be turned to move the cutter bar in an endwise direction along its guideway relative to the hanger frame so that the tension of the cutter chain may be varied as desired. When the adjusting screw has been adjusted to move the cutter bar into the desired position, the gibs 23 may be tightened to clamp the parts firmly in position.

By arranging the bar adjusting screw wholly outside of the cutter bar in the manner disclosed, and by the provision of the gibs and guides arranged in the manner set forth, the cutter bar may be made up of plates and bar members without the necessity of slotting the plates to receive the adjusting screw within the cutter bar, as in previous known devices. Further by adjustably guiding the cutter bar relative to the hanger frame in the manner disclosed the cutter bar is not only made more rugged but also is supported in an improved manner. By the provision of the keys and key blocks, lateral stresses on the bar rivets and gibs are minimized, resulting in a more rugged construction, and by tightening the gibs the parts may be firmly held in adjusted position. Further by the provision of the improved hanger frame structure, the cutter bar is supported in an improved manner, and by the particular disposition of the bar on the hanger, slotting or otherwise weakening of the cutter bar is eliminated resulting in a stronger construction. These and other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What we claim as new and desire to secure by Letters Patent is:

1. A kerf cutting apparatus comprising, in combination, a hanger frame providing a guideway, a

cutter bar, a member carrying said cutter bar and guided on said guideway for adjustment relative to said frame in a direction lengthwise of said bar, means for rigidly securing said bar to said 5 adjustable member for adjustment therewith, a sliding interlocking connection between said frame and said member for reducing the transmission of lateral stresses to said guideway while permitting adjustment of said member, said interlocking connection being effective irrespective 10 of the adjusted position of said member on said guideway, and a rigid interlocking connection extending in parallelism with said sliding connection and disposed between said bar and said member 15 for reducing the transmission of lateral stresses to said securing means.

2. A kerf cutting apparatus comprising, in combination, a hanger frame providing a guideway, a cutter bar, a member carrying said bar and guided on said guideway for adjustment relative to said frame, a key and slot connection between said frame and said member for reducing the transmission of lateral stresses to said guideway, means for rigidly securing said bar to said member, a key and slot connection between said bar and said member for reducing the transmission of lateral stresses to said securing means, and adjustable means arranged between said member and said frame for adjusting said member on its 25 guideway, the key of said first mentioned key and slot connection sliding in the slot thereof during such adjustment.

3. A kerf cutting apparatus comprising, in combination, a hanger frame providing a guideway, a cutter bar, a member carrying said cutter bar and guided on said guideway for adjustment relative to said frame in a direction lengthwise of said bar, a sliding interlocking connection between said frame and said member for reducing the transmission of lateral stresses to said guideway while permitting free adjustment of said member, said sliding connection being effective irrespective of the adjusted position of said member on said guideway, elements for rigidly securing said bar 40 and said member together, and rigid interlocking connection between said bar and said member for reducing the transmission of the lateral stresses to said securing elements.

CLYDE P. BALDWIN.

HARRY H. VANDERZEE.
